UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,474, dated September 13, 1881.

Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

A is a large bouquet of roses, containing also a prominent leaf, *a*, and series of projecting fern-leaves, *b*. B is another large bouquet, of roses and other flowers, having also projecting fern-leaves *d*. C and D are two other bouquets, of roses and other flowers. These four bouquets are placed on a background which is 10 divided into series of fields by straight or angular lines. Thus between figures A and B is a field, E, containing a ground of crosses, *e*, and a V-shaped ornament, *f*, on each cross. Above the figure B is a field, F, containing zig-zag lines that form partly-closed squares, the 15 said squares being alternately open at the upper and lower sides, as shown. Adjoining field F, between figures B and C, is a field, G, which is divided into rows of larger and smaller 20 alternating squares, each larger square containing an inner geometrical rosette. Below field G is a field, H, which is ornamented by V-shaped figures *f*, similar to those in field E. Below the field H, and above figure D, is a 25 field, I, which is divided into squares *g*, each

square being traversed by two peculiarly-bent lines, and every alternate square containing a smaller inner square, as shown. To the right of figure A is a field, J, which contains series of double squares connected by diagonal lines, 40 as shown.

I claim—

1. The design for carpets, consisting of the ornamentation of the field E, substantially as shown. 45
2. The design for carpets, consisting of the ornamentation of field F, substantially as shown.
3. The design for carpets, consisting of the ornamentation of field G, substantially as 50 shown.
4. The design for carpets, consisting of the ornamentation of field H, substantially as shown.
5. The design for carpets, consisting of the ornamentation of field I, substantially as 55 shown.
6. The design for carpets, consisting of the ornamentation of field J, substantially as shown. 60
7. The design for carpets, consisting of the figures A, B, C, and D, substantially as shown.
8. The design for carpets, consisting of the figures A B C D E F G H I J *a b d e f g*, substantially as shown.

HENRY HORAN.
